UNITED STATES PATENT OFFICE

105,452

DESIGN FOR AN INDIRECT ELECTRIC LIGHTING FIXTURE

Clyde Poling, Fairmont, W. Va., assignor to West
Virginia Lighting Co., Inc., Fairmont, W. Va., a
corporation of West Virginia

Application April 16, 1937, Serial No. 68,823

Term of patent 3½ years

To all whom it may concern:

Be it known that I, Clyde Poling, a citizen of the United States of America, residing at Fairmont, in the county of Marion and State of West Virginia, have invented a new, original, and ornamental Design for an Indirect Electric Lighting Fixture, of which the following is a specification, reference being had to the accompanying drawing, forming a part thereof.

In the drawing:

Figure 1 is a side elevation of an indirect electric lighting fixture showing my new design, and
Figure 2 is a bottom plan view.

I claim:

The ornamental design for an indirect electric lighting fixture, as shown.

CLYDE POLING.
